UNITED STATES PATENT OFFICE.

LOUIS A. DE MAYO, OF NEW YORK, N. Y.

APPARATUS FOR COALING VESSELS.

No. 797,364.

Specification of Letters Patent.

Patented Aug. 15, 1905.

Application filed December 31, 1903. Serial No. 187,345.

To all whom it may concern:

Be it known that I, LOUIS A. DE MAYO, a citizen of the United States, and a resident of the city of New York, borough of Manhattan, in the county and State of New York, have invented a new and Improved Apparatus for Coalizing Vessels, of which the following is a full, clear, and exact description.

This invention relates particularly to an organized apparatus for coalizing and approximately trimming the bunkers of modern vessels, particularly the modern sea-going steamers. Under the practice heretofore followed the trimming of the coal in the bunkers constitutes the principal part of the work of coalizing a ship, since usually the coal is merely elevated to the coaling-port and then trimmed by hand.

The prime object of my invention is not only to elevate the coal to and distribute it into the coaling-port of the ship, but to provide means for distributing the coal into the various bunker-hatches, thus reducing to a minimum the work of hand-trimming. I attain this end by providing, in combination with the elevator proper, a peculiarly-arranged distributor which takes the coal from the elevator proper and conducts it to any desired point within the interior of the ship, this distributing means being extensible and adjustable and being of such structure that it may be taken apart and removed from the ship through the coaling-port thereof.

A further object of the invention is to provide means for sustaining the elevator proper flexibly in position alongside of the ship, so that any movement of the barge from which the coal is taken will not destroy or rack any of the parts of the apparatus and as the coal-level lowers in the barge the elevator will be capable of dropping down to meet the gradually-lowering level of the coal.

A further object is to so construct the elevator proper that it will discharge all of the coal from its spout without spilling any back into the barge or overboard. It has heretofore been a great disadvantage with apparatus of this sort that considerable of the material handled was spilled from the elevator. By means of the peculiarly-constructed elevator which I have provided I insure the delivery from the elevator of all of the coal taken in the buckets thereof.

A still further object of the invention is to so arrange the delivery-chute which leads to the coaling-port that this may be readily ad-

justed to suit the gradual settling of the elevator due to the lowering of the coal-level within the barge.

In attaining these and various minor objects I provide a concrete organism by means of which a continual stream of coal is kept in motion from the barge to the bunkers, thus expediting the work of coalizing the ship, the apparatus being completely removable from the ship after the operation has been finished, so that it may be transported from one point to another with perfect convenience.

This specification is an exact description of one example of the invention, while the claims define the actual scope thereof.

Reference is to be had to the accompanying drawings, forming a part of this specification, in which similar characters of reference indicate corresponding parts in all the figures.

Figure 1 is a view showing a general outline of the ship and coal-barge in section and illustrating the operative position of my apparatus with respect thereto. Fig. 1^a is a fragmentary side elevation particularly showing the elevator and the guiding means therefor, which allows the elevator to drop into the barge, as hereinbefore explained. Fig. 2 is an enlarged longitudinal section of the elevator proper, showing the buckets, belt, and spout thereof. Fig. 3 is a still further enlargement showing one of the buckets in section on the line 3 of Fig. 4 and illustrating also the hexagonal drum at the top of the elevator proper. Fig. 4 is a front elevation of a part of the conveyer-belt, showing one of the buckets in section on the line 4 4 of Fig. 3. Fig. 5 is a longitudinal section of the distributor, illustrating the manner of extending or contracting the same and the means for adjustably mounting it. Fig. 6 is a plan view of these parts, and Fig. 7 is an inner end elevation of the same.

As shown best in Fig. 2, the elevator proper has a framing 10, formed of longitudinal beams with suitable bracings between them. This frame 10 is provided at its upper end with a tackle 11, which may be hung from one of the ship's davits, as illustrated in Fig. 1, or from a crane or other means with which the ship may be ordinarily or especially provided. 12 indicates a number of guy-tackles which extend between the frame 10 and the barge. Preferably these tackles are three in number, two extending to the respective ends of the barge and one being fastened to the

outboard-rail thereof. Attached to each side of the frame 10 on the corners adjacent to the ship are longitudinally-extending rails 14, on which fit loosely sleeves 15. To these sleeves are pivoted guy-rods 16. Said rods have hooks 17 at their opposite ends, and these hooks are adapted to be engaged with the rail or other convenient part of the ship at each side of the elevator proper in the manner illustrated in Figs. 1 and 1^a. The lower end of the elevator proper dips into the barge, as shown, and it may be observed that by means of the peculiar supporting-tackles and guys the elevator proper is flexibly sustained in its operative position and by slackening away on the tackle 11 as the occasion requires the elevator may be allowed to drop into the barge, so as to keep its bottom properly sunk in the coal therein. In the lower end of the elevator-frame 10 is arranged a hexagonal drum 18, which is suitably mounted therein, and in the upper end of the frame a similar drum 19 is located, the upper drum 19 being provided, however, with a pulley-face over which passes a suitable driving belt or chain 20. This belt or chain also passes over a pulley 21, mounted below the drum 19 and connected with a larger pulley 22, over which passes a suitable belt or chain 23 from a motor 24. The motor is preferably of the electric type and is sustained inside of the frame 10, thus producing a compact arrangement and protecting the motor from damage during the handling of the apparatus. Passing over the hexagonal drums 18 and 19 is the conveyer-belt, which is made up, as shown in Figs. 2 and 4, of a number of plates 25, joined to each other by hinges 26, thus forming a continuous web-like belt or apron which prevents the passage of coal through it for a purpose which will be hereinafter fully set forth. The plates 25 are so proportioned that they will correspond to the hexagonal sides of the drums 18 19 and run evenly over the same in the manner indicated in Fig. 2. Attached to alternate of the plates 25 are the elevator-buckets 27, which are open at the top, as shown, and are preferably of a triangular form. At the lower part of the frame 10 and at the outer side thereof is located a shield 28, which lies opposite and above the lower drum 18 and which serves to prevent particles of coal being thrown out from the boot of the elevator by the action of the buckets 27 moving rapidly into the coal. At the inner side of the upper part of the frame 10 and in line with the lower portion of the drum 19 is located an apron 29, rigidly mounted on the frame and adapted to have the buckets discharge thereinto. Mounted adjacent to the apron 29 and forming a continuation thereof is an extensible delivery-spout. This spout may be of any form desired, but is preferably constructed of a number of sections 30, hinged together, as indicated at 31, and pro-

vided with latches 32, by which they may be locked in alinement with each other, as shown with respect to the two upper sections in Fig. 2. The uppermost section 30 is connected by a hinge 33 to the frame 10 and provided with an extensible brace 34, so that it may be adjusted to the position desired. From the apron 29 a shield 35 extends down the inner side of the elevator to the bottom thereof, effectually walling in this inner side, so as to prevent the loss of coal which may escape the apron 29. With reference to this construction it may be seen that the coal lying in the upwardly-moving buckets will begin to fall from the buckets when they assume the uppermost position shown with respect to one of the buckets in Fig. 3. The coal will fall forward in the direction of the movement of the buckets, and by means of the continuous conveyer-belt formed by the jointed plates 25 the coal is guided forward along the conveyer-belt until it strikes the bottom of the inverted next adjacent bucket, which then forms a sort of chute, guiding the coal outward into the apron 29 and from thence into the chute proper. By this means, therefore, I am able to direct into the chute practically all of the coal lifted by the buckets. The almost imperceptible percentage of coal which escapes the apron 29 will fall inside of the shield 35 and be returned to the barge. It will thus be seen that by means of the apparatus which I have provided it is impossible for any part of the coal to be lost overboard in the loading operation.

The apparatus is adjusted with respect to the ship so that the extensible chute will project either into or directly adjacent to the coaling-port of the ship. In Fig. 1 it is shown projecting directly adjacent to the coaling-port; but if the distributor-hood be arranged as shown in Fig. 5 the chute should then be projected into the port, so as properly to discharge the coal into the distributor.

36 indicates the hood, which is fitted in the coaling-port and may or may not form a part of the distributor, as desired.

The distributor comprises two sections 37 and 38, having extensible connection with each other in any desired manner—for example, by the overlapping parts 39. (Best shown in Fig. 5.) Each section 37 and 38 is provided with a drum 40, and over these drums passes the conveyer-belt 41, which may be of any desired form. One of the sections, preferably the section 38, is provided with a number of rollers 42, over which the conveyer-belt is run in the manner shown in Fig. 5, so that the extension or contraction of the conveyer will not affect the necessary tautness of the belt.

43 indicates a motor which is mounted in the section 38 and connected by a train of gear elements 44 with the drum 40 thereof, so as to drive the drum, and consequently

the apron. The motor 43 is preferably of the electric type, and the gearing 44 may be of any sort desired—for instance, the belt-and-pulley arrangement shown.

At the receiving end of the conveyer a boot 45 is located, this boot being juxtaposed to the coal-port of the ship, so that as the coal is discharged from the chute into the port it is gathered by the boot 45 and guided onto the apron or belt 41, which moving inward carries the coal to the inner end of the distributer and discharges it therefrom.

In Fig. 6 various of the bunker-hatches are illustrated, and the distributer is arranged to deliver the coal first to one bunker and then to others as the bunkers are filled. To facilitate this adjustment of the distributer, I mount the receiving end thereof on a step-bearing 46, and the outer end is arranged to run on an arc-shaped track 47, connected with the bearing 46 by extensible braces 48, so that the track 47 may be moved outward from the step-bearing to follow the extension of the conveyer. Said track 47 is formed in sections, so that its shape may be changed at will to correspond with the arc in which the outer end of the conveyer runs. At the outer end of the conveyer rollers 49 are located, these rollers being best shown in Fig. 7 and being carried on rods 50. Said rods have threaded portions working in nuts 51, stationary on the conveyer-section 38, and hand-wheels 52 are attached to the upper ends of the rods to facilitate the turning thereof. The lower ends of the rods are joined to the bearings of the rollers 49 by a connection 52, which facilitates the turning of the rods in the roller mounts or bearings. By this mechanism the inner or discharge end of the conveyer may be raised or lowered at will. It will be seen that by mounting the conveyer as described it may be turned around the center 46, so as to reach any of a group of bunker-hatches, and it also may be extended or contracted for the same purpose.

In the practical operation of the apparatus the barge is brought alongside of the ship, as is customary, and the elevator proper is adjusted so as to discharge into the coal-port. The conveyer is assembled within the ship and arranged with the receiving end adjacent to the coal-port, so as to take the coal from the discharge-chute of the elevator proper. The operation of the elevator proper and the conveyer is then started, and the coal is carried into the bunker in a continuously-moving stream. After one of the bunkers has been filled the operation may be stopped for a sufficient period to enable the conveyer to be shifted to the next hatch, and so on until all of a certain group of bunkers have been filled. The elevating apparatus may then be shifted to another coal-port and the conveyer correspondingly changed, this operation going on until the complete coaling of the ves-

sel has been effected. By this apparatus, therefore, I am enabled to do the greater part of the coaling mechanically, leaving only the mere trimming of the individual bunkers for manual work.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. In an apparatus for coaling ships, the combination of an elevator, means for mounting the same outside of the ship, a discharge-chute leading from the elevator to the coal-port of the ship, a distributer located within the ship and receiving the coal from the elevator discharge-chute, and mechanism for driving the elevator and distributer; the said distributer comprising an apron and extensible frame-sections, for the purpose specified.

2. In an apparatus for coaling ships, the combination of an elevator, means for mounting the same outside of the ship, a discharge-chute leading from the elevator to the coal-port of the ship, a distributer located within the ship and adjacent to the coal-port and receiving the coal from the discharge-chute, a step-bearing for the outboard end of the distributer, and a curved track on which the inboard end of the distributer runs.

3. In an apparatus for coaling ships, the combination of a frame, an elevating means mounted therein, mechanism for driving the elevating means, a centrally-located suspension means attached to the upper part of the frame and connecting it with the ship, and a guy-arm at each side of the frame; said arms having sliding connection with the frame, and being adapted to engage the ship.

4. In an apparatus for coaling ships, the combination of an elevator, means for suspending the same from the ship at one side thereof, means for operating the elevator, a discharge-chute leading from the upper portion of the elevator to the coaling-port of the ship, a distributer located within the hold of the ship and extending horizontally from the coal-port to distribute or trim the coal, and means for operating the distributer.

5. In an apparatus for coaling ships, the combination of an elevator, means for suspending the same from the ship at one side thereof, means for operating the elevator, a discharge-chute leading from the upper portion of the elevator to the coaling-port of the ship, a distributer located within the hold of the ship and extending horizontally from the coal-port to distribute or trim the coal, and means for operating the distributer, the distributer having a hood projecting to the coal-port to receive the coal from the chute.

6. In an apparatus for coaling ships, the combination of an elevator arranged to discharge into the coal-port in the side of the ship, means mounted on the vessel for suspending the elevator from the vessel at one side thereof, means for operating the elevator, and means within the vessel for horizontally distributing the coal said means extending from the coal-port.

7. In an apparatus for coaling ships, the combination of a frame and elevating means thereon, means for driving the elevating means, the driving means being mounted on the frame, means mounted on the ship and connected with the upper part of the frame to suspend the same from the ship, and guy devices at each side of the frame said devices being in connection with the frame and with the ship.

8. In an apparatus for coaling ships, the combination of a frame and elevating means thereon, means for driving the elevating means, the driving means being mounted on the frame, means mounted on the ship and connected with the upper part of the frame to suspend the same from the ship, and guy devices at each side of the frame said devices being in connection with the frame and with the ship, and said devices comprising arms adapted removably to engage the ship and having sliding connection with the elevator-frame.

9. The combination of an elevator-frame, elevating devices mounted thereon and comprising drums, an endless belt running over the same, the belt being formed of a series of plates hinged together, and buckets attached to the belt, a discharge-chute mounted on the frame, and a shield mounted on the frame and extending along the same downward from the discharge-chute.

10. The combination of a frame, elevating devices mounted thereon, a discharge-chute at the upper part of the frame and receiving the material handled from the elevating devices, and a shield attached to the frame and

extending along the same downward from the discharge-chute.

11. In an apparatus for coaling ships, the combination of an elevator, means for mounting same outside of the ship to discharge the coal through the coaling-port, a distributer located in the hold of the ship to trim or distribute the coal horizontally therein, and means for mounting the distributer to be adjusted by turning it around a center adjustable to the coal-port or receiving end of the distributer.

12. In an apparatus for coaling ships, the combination of an elevator arranged to discharge into the coal-port of a ship, means mounted on the vessel for suspending the elevator from the vessel at one side thereof, means for operating the elevator, means within the vessel for horizontally trimming or distributing the coal, said means extending from the coal-port and means for operating said trimming or distributing means.

13. The combination of a frame, drums mounted respectively at the end portions thereof, the drums being of angular cross-sectional form, elevating devices mounted on the drums and comprising a number of plates hinged together to form a continuous endless belt or apron, the belt or apron running over the drums and the plates of the belt or apron being of a length corresponding to the width of the plain faces of the said angular drums and the elevating devices also comprising buckets attached to certain of the plates, the buckets being spaced from each other and having a plate of the apron intervening each bucket and the buckets adjacent thereto, and means for operating the elevating devices.

In testimony whereof I have signed my name to this specification in the presence of two subscribing witnesses.
